HYDRAULIC PUMPING JACK

John Conley Mason, Greggton, Tex.

Application August 8, 1950, Serial No. 178,308

12 Claims. (Cl. 60—52)

1

This invention relates to pumping jacks and is particularly concerned with long-stroke hydraulic pumping jacks of the general type employed to operate conventional plunger type bottom hole pumps.

Hydraulic pumping jacks of the character above referred to have heretofore been characterized by the use of pumps with a constant discharge, the discharge port of which is alternately connected to a cylinder at one side of a reciprocating piston and to an air balance accumulator tank, and the intake of which is likewise alternately connected to said cylinder at said side of the piston and the said air balance accumulator tank. This reversal of the order of the pump is automatically accomplished by means of a reversing valve mechanism. The piston is, of course, connected to the polished rod of the pump so that when the hydraulic pressure from the pump is exerted against the piston, the upstroke of the pump is effected. The piston on the down stroke, through the medium of the hydraulic system, effects counterbalancing of the pump during such down stroke.

Consequently, when the pumping jack is in operation, a constant flow of fluid under sufficient pressure is exerted against the piston to effect the up stroke of the pump, and at the top of the up stroke, the reversing valve operates to reverse the order of the pump. Upon such reversal the fluid under pressure at the underside of the piston is pumped by the pump back into the air balance tank, wherein the pressure is adjusted so as to effect counterbalancing. At the end of the down stroke, of course, the reversing valve acts to recommence the cycle just described. Obviously, such prior pumping jacks, because of the use of a pump with a constant discharge and a prime mover therefor driven at a uniform speed, were of relatively low efficiency in that they provided for no compensation for the varying loads and work through a pumping cycle.

It is, therefore, among the primary objects of the present invention to provide a hydraulic pumping jack having a relatively high efficiency and in which the necessity for reversing valve systems is eliminated.

It is another object of the present invention to provide a hydraulic pumping jack having a hydraulic system including a centrifugal pump and a directly connected internal combustion engine, which are so associated with the hydraulic system that, by merely adjusting the throttle positions of the latter, the system may be easily and quickly adjusted to suit different pumping and counterweighted loads.

It is a further object of the present invention to provide a hydraulic pumping jack of the long-stroke type in which the length of the stroke may be easily changed, and in which the reversal of direction of movement at the ends of the stroke is effected without the use of mechanically operated valve devices and in a cushioned manner so as to avoid unnecessary strains and shocks to the mechanism.

10 One form which the invention may assume is exemplified in the following description and illustrated by way of example in the accompanying drawings, in which:

15 Fig. 1 is a schematic diagrammatic illustration of a pumping jack embodying the preferred form of the invention.

20 Fig. 2 is a fragmentary vertical sectional view illustrating the jack cylinder and piston of the present invention and disclosing certain details of construction.

25 Fig. 3 is a diagrammatic view of the pumping jack and its hydraulic system and controls therefor.

30 Fig. 4 is a view similar to Fig. 3 except the parts are shown in the position they assume when the prime mover is in a decelerated throttle position.

Referring more particularly to the accompanying drawings, there is there disclosed a pumping apparatus embodying the preferred form of my invention. This apparatus includes an elongated jack cylinder 10 to be arranged vertically over the well to be pumped. For this purpose the cylinder is mounted on a rigid supporting frame 11, preferably having skid rails 12 so that for the purposes of cleaning or repairs to the well or the pump, the rig may be skidded to a non-obstructing position.

35 Reciprocably mounted in the cylinder 10 is a piston 14 having a piston rod 15, which is, of course, the polished rod of the pump in the well. It is intended that the present pumping jack be employed to operate conventional plunger-type bottom hole pumps having a long stroke.

40 Inasmuch as such pumps form no part of the present invention, one is not disclosed herein, it being sufficient for the present purposes to set forth that the polished rod 15 is connected in the usual manner to the sucker rod assembly of the pump.

45 It is intended to provide hydraulic pressure within the cylinder 10 at the underside of the piston 14 for the purpose of moving the piston upwardly in the cylinder 10 to effect the upstroke of the pump. It is further intended that, when this piston reaches the top of the upstroke,

the pressure beneath the piston 14 in the cylinder 10 be reduced to an amount that the well load imposed upon the piston will cause it to move downwardly and effect the down stroke of the pump. During this down stroke of the pump, the resistance of hydraulic fluid in the cylinder 10, which cylinder forms part of the hydraulic system, is such as to properly counterweight the well load on the piston so that the down stroke will be effected at a constant and desired rate of speed. On the upstroke, of course, sufficient pump pressure or hydraulic pressure is exerted beneath the piston 14 to effect a desired rate of travel of the piston upwardly. As the piston reaches approximately the end of its down stroke, its downward movement is arrested by increasing the hydraulic pressure at the underside of the piston so as to reverse its direction of movement and recommence the cycle just described.

In general, the hydraulic system for operating the piston 14 is a closed one and it includes a centrifugal pump 16 directly connected to a prime mover 17 which in this instance is shown as an internal combustion engine. In the hydraulic system there is also an air balance tank 18, which is connected to the intake port of the centrifugal pump 16. The discharge port of the centrifugal pump 16 is connected to the interior of the bottom of the cylinder 10 through the medium of a pipe line 19. The system, therefore, is a closed hydraulic system and sufficient pressure is maintained in the air balance tank 18 which, together with other inherent features of the system, will properly counterbalance the well load on the piston 14 on the down stroke of its cycle.

Along the length of the cylinder are two sets of spaced control orifices, that is to say, a set of upper control orifices or ports A and a set of lower control orifices or ports B as shown in Figure 1. The orifices of the group A are indicated in the drawings by the numeral 20 (Figs. 3 and 4) and the orifices of the lower set B are indicated by the numeral 21 (Figs. 2 and 4). The orifices 20 of the set A all communicate with a manifold 22 through individual manually operated valves 23. The group of control orifices B is also connected with a control manifold 24 through manually operated individual valve 23. It is one of the functions of the control orifices 20 and 21 to regulate or adjust the length of the piston stroke. To effect the maximum stroke, the uppermost valve of the group A of the orifices 20 would be open to render the uppermost orifice 20 effective, while the remainder are closed to render the remainder of the orifices 20 ineffective, and the lowermost valve of the group B of the orifices 21 will be open to render the lowermost orifice 21 effective, while the remainder are maintained closed and ineffective by their associated valves. The manner in which the orifices 20 and 21 selectively adjust or change the length of the pumping stroke will be clear from the further explanation herein of the operation of the pumping jack.

The manifold 22 of the orifice group A is connected by a tubing 22a to an engine speed control element 26, while the manifold 24 of the group B of the orifices is connected by conduit 24a to an engine speed control element 27. These control elements 26 and 27 and their association with the hydraulic system are more clearly disclosed in Figs. 3 and 4 of the drawings. Reference being had to these latter figures, it will be seen that the internal combustion engine 17, which is directly connected to the centrifugal pump 16

for driving the same, is fitted with a throttle lever 28 having a toggle spring 29 fitted thereto, which spring tends to hold the throttle either in wide open "accelerated position" or completely closed "decelerated position." By "closed or decelerated position" is meant a position wherein the engine will either merely idle or operate at such a slow speed that the downward load on the piston will cause the piston to descend and reverse the fluid flow through the pump 16, although the pump continues to rotate in its normal direction. By "open or accelerated position" is meant a throttle position driving the pump at such a speed that its output will be sufficient to drive the piston through its upstroke at a desired rate of speed.

The throttle lever 28 is connected by a connection 30 to a throttle control lever 31. This latter is connected with the piston rod 32 of the piston 32a of the control element 26 and also with the piston rod 33 of the piston 33a of the control element 27. Each of these control elements includes a cylinder in which its associated piston is reciprocable. The positions of the pistons 32a and 33a are influenced by the fluid pressure in the cylinder 10 which is led to the cylinders through the medium of the conduits 22a and 24a connecting the manifolds 22 and 24 to the control elements 26 and 27. The piston 32a of control element 26 is solely influenced by the pressure of the fluid entering the same, while the piston 33a of the control element 27 is spring-loaded by means of a spring 34 which, to a predetermined degree, opposes or modifies the influence of the fluid pressure on the piston. A lost motion device 35 is provided between the piston rod 33 of the control element 27 and the throttle control lever 31 for the purpose which will be hereinafter described.

However, it is the purpose of the control elements 26 and 27 and their connection with the interior of the cylinder 10, and their connection with the throttle of the prime mover or internal combustion engine 17 which drives the centrifugal pump 16, to so regulate the operation of the prime mover 17 and hence the pump 16 to effect the reciprocation of the piston 14 and its associated pumping mechanism. That is to say, when the piston is at the bottom of its stroke, as illustrated in Fig. 3 of the drawings, and assuming that the lowermost control orifice 21 is open to its manifold 24, the piston 14 being disposed below the orifice 21 and uncovering the same, the latter is subjected to atmospheric pressure. This is due to the fact that the upper extremity or end of the cylinder 10 communicates with the atmosphere through a filter breather cap 10a. Consequently, there being atmospheric or a relatively low pressure of that order against the piston 33a of the control element 27, its spring 34 will overcome that pressure and urge the piston rod 33 and its associated piston to the position shown in Fig. 3, moving the throttle 28 to accelerated or open position. At this accelerated or open throttle position, the centrifugal pump will be driven so as to pump fluid from the air balance tank 18 through the pipe line 19 into the cylinder 10 at the underside of the piston 14, which pressure will be sufficient to effect the upstroke of the pump. Naturally, the operator knowing the well load to be elevated can adjust the open or accelerated throttle position of the internal combustion engine so that the output of the centrifugal pump 16 will suit the requirement, that is, the

requirement of effecting the upstroke of the pump at the speed desired by the operator.

Thus, by merely adjusting the position of the open or accelerated throttle position to the pump capacity desired, the operator may regulate the speed of operation of the well pump as well as compensate for different pumping loads. Of course, it should be understood that pumps of different well depths have different pumping loads and, therefore, as the present pumping jack has the facilities herein set forth, it can be easily accommodated to pumping wells of different depths under varying well conditions.

Under the influence of the pump pressure, the piston 14 will travel upwardly from the position shown in Fig. 3 to a position shown in Fig. 4, at which time it will have passed and uncovered the upper control orifice 20 of the upper group A. Prior to the time that the piston 14 uncovered this port 20 to place it in communication with the interior of the cylinder 10 at the underside of the piston 14, that control port 20 was in communication with the atmosphere. However, immediately that it is placed in communication with the underside of the piston 14, it is then subjected to the pressure of the pump 16, which pump pressure will exert its force against the piston 32a of the control element 26 sufficiently to overcome the force of spring 34 and moving with it the piston rod 33 of the piston 33a of the control element 27. In so operating, it will also overcome the force of the toggle spring 29 and cause the throttle lever 28 to snap to the closed or decelerated throttle position. This will automatically cut down the delivery of the centrifugal pump to the underside of the piston 14 in the cylinder 10.

Immediately that this is accomplished, the weight imposed upon the piston 14 by the well load through the polished rod 15 will cause the piston 14 to reverse its direction of travel and commence its down stroke under the influence of that force. The downward movement of the piston 14 will cause the fluid to flow in a reverse direction from the lower end of the cylinder 10 through the pipe line 19 into the discharge port of the centrifugal pump and through the centrifugal pump and its intake port into the air balance tank 18 against the pressure which is maintained in the tank or accumulator 18. This pressure would be such as to effect a proper counterbalance of the load on the piston 14.

However, an additional control medium is provided in this respect by the setting of the closed or decelerated throttle position. That is to say, if the throttle position, although we have termed it "closed" here, is set at a relatively slow speed, the resistance of the centrifugal pump to the reverse flow of the liquid through it would be at one value, where if the pump speed is changed, that resistance would be changed to a different value. Therefore, by regulating the decelerated or closed throttle position, the resistance at the centrifugal pump 16, in addition to the back pressure in the air balance tank 18, may be utilized to counterbalance the well load to a desired degree.

What has been just described with respect to the lowermost and the uppermost of the orifices 20 and 21 takes place regardless of which of the orifices of the group A and group B are selected to determine the effective length of the pump stroke. Naturally, by opening the uppermost of the orifices 20 and the lowermost of the orifices 21, the maximum length of pump stroke is effected.

In this instance, I have shown an additional means of cushioning the end of the stroke of the piston when the maximum stroke length is employed. This includes the plungers 40 and 40a on opposite sides of the piston 14, which are adapted to enter orifices 41 and 42 at the upper and lower ends of the cylinders. The plungers 40 and 40a are tapered so that as they enter and project through the orifices 41 and 42 at the opposite end of the piston stroke, a dash-pot action will be created so as to cushion the stopping of the piston at the stroke end. Obviously, the piston will travel some distance past the selected effective orifices 20 and 21 at opposite ends of their stroke. Of course, if the stroke of the piston is shortened, the stroke termination would be cushioned purely by the fluid through the medium of the change in the fluid pressure on opposite sides of the piston.

It is obvious from the foregoing that the length of the piston stroke may be varied by merely selection of the proper orifices 20 and 21 complementary to the length of the piston stroke required. Therefore, the piston stroke can be relatively short or can be the maximum permitted by the length of the cylinder 14. Consequently, the pumping jack here shown will be adapted not only to varying pumping conditions, that is to say, well depth, but it can also be adapted to different types of pumps to accommodate different strokes thereof.

In operation of the pumping jack, it is constructed substantially as illustrated and described herein. Assuming that the piston is in its lowermost position as illustrated in Fig. 3 of the drawings, the fact of atmospheric pressure in the control elements 26 and 27 will cause the spring 34 to overcome the spring 29 and move the throttle to open or accelerated position. Of course, the throttle had been previously positioned with consideration to the well load as well as the pumping speeds desired. As previously stated, the operator can compensate for these factors by the throttle setting. Immediately that the prime mover commences operation, the centrifugal pump 16, drawing its liquid from the air balance tank 18, will pump the same into the bottom of the cylinder 10 at the underside of the piston 14, the pump output and pressure being sufficient to elevate the piston 14 and effect the upstroke of the pump at the desired rate of speed.

The fact that the piston, shortly after commencing the upstroke, uncovers the selected port 21 will not affect the operation of the throttle setting of the prime mover, the reason being that, although this pressure will be communicated to the control unit 27, the lost motion device 35 prevents it from affecting the throttle position.

The piston continues to move upwardly until it passes over the selected control port 20, placing that port in communication with the cylinder 10 at the underside of the piston 14. At that time pressure is immediately transmitted through the selected effective control port 20 and its associated manifold to the control element 26, moving the piston 32a therein to its opposite condition which, through the medium of its rod 32, moves the throttle control rod 31 to a point where the throttle lever 28 is snapped to closed or decelerated position. Immediately that this occurs, of course, the fluid delivery to the underside of the piston in the cylinder 10 is cut off and the piston 14 will reverse its direction of

travel and commence to descend due to the gravitational pull of the load thereon. As the piston 14 descends, it and the load carried thereby will be counterbalanced by the resistance to the fluid flow offered by the centrifugal pump 16 and the pressure in the air balance tank 18.

As previously stated, the speed of descent as well as different varying well loads may be compensated for, not only by varying the pressure in the air balance tank 18, but also by setting the closed or decelerated throttle position of the prime mover at a point whereby the pump 16 will offer the additional desired resistance to the reverse flow of fluid therethrough to the tank or accumulator 18.

When the piston 14 has descended to a point where it again uncovers the selected control port 21 and places the same in communication with the cylinder at the upper side of the piston 14, the drop in pressure at the control element 27 will cause the spring 34 to again overcome the spring 29 on the throttle lever 28 so as to move the throttle control lever 31 a sufficient distance to throw the throttle lever 28 again to open or accelerated throttle position. By providing a toggle spring connection for the throttle lever 28, galloping or minor variations in engine speed will be avoided because the throttle position at either open or closed position will remain constant.

Obviously, the operation of the pumping jack is identical regardless of which ports of the sets of control ports A and B are selected to be effective. If the maximum stroke is desired, of course, the uppermost control port 20 and the lowermost control port 21 are rendered effective by opening of the associated valve of the control ports A and B and closing the remainder. Thus, by mere selection of proper control ports 20 and 21, the length of the stroke of the piston may be determined. Also, by simply changing the setting of the throttle position, the speed of the upstroke as well as the speed of the down stroke of the pump may be maintained at a predetermined constant.

Obviously, the reversal of the piston 14 is effected without the necessity of providing reversing valves or any other mechanically operated mechanism. Also, it is obvious that the termination of the piston strokes will be effected without any sudden shock or strain being placed on the system due to the fact that the reversal of the pump pressure is not instantaneous so that the piston is decelerated to a stop and then accelerated to top speed.

I also wish to point out that any hydraulic fluid accumulating on top of the piston 14 will ultimately discharge through a scavenger port 43, a scavenger tubing 44 to a scavenger tank 45. This tank 45 is connected to the intake of a small pump 46, which is driven by a small electric motor 47. The circuit of this motor includes a switch which is actuated by a float 48 in the scavenger tank 45, so that when the level of liquid in the tank 45 rises to a predetermined point, the circuit of the motor 47 is closed, operating the pump 46 and discharging the liquid from the tank 45 back into the closed hydraulic system of the pump 16. The discharge from the pump 46 is connected by a tubing 50 to the hydraulic system at a point adjacent the discharge of the centrifugal pump 16 as illustrated.

While I have shown the preferred form of my invention, it is to be understood that various changes may be made in its construction by those skilled in the art without departing from

the spirit of the invention as defined in the appended claims.

Having thus described my invention, what I claim and desire to obtain by Letters Patent is:

1. A pump jack including a stationary elongated vertically positioned cylinder having a closed lower end, the upper end of the cylinder being in communication with the atmosphere, a piston reciprocably mounted in the cylinder for connection at its lower end to a pump rod extending through the lower end of the cylinder, a hydraulic circuit for operating the piston including a centrifugal pump having its discharge connected to the lower end of the cylinder beneath the piston and its intake connected with an accumulator tank, pressure responsive pump control means associated with the cylinder for automatically causing increase of the pump output to elevate the piston at the end of the down stroke thereof and to automatically decrease the pump output at the end of the upstroke thereof to enable the piston to lower under the influence of the load thereon at the end of the upstroke.

2. A pumping jack including an elongated vertically positioned cylinder, a piston reciprocably mounted therein and adapted to be connected at its lower end to a pump rod for operating the same, the lower end of said cylinder being fluid tight, a hydraulic circuit for operating the piston including a centrifugal pump having its discharge connected to the lower end of the cylinder at a point beneath the piston and having its intake connected with an accumulator tank, a prime mover for driving the centrifugal pump, said prime mover having an accelerated speed position sufficient to drive the pump at a speed producing an output sufficient to elevate the piston and its load through its upstroke and having a decelerated speed position for driving the pump at a rate where the load on the piston will cause lowering of the same and reverse the fluid flow through the pump to the accumulator tank, and means automatically operable to move said prime mover to the accelerated or decelerated position depending on the position of the piston in the cylinder.

3. A pumping jack including an elongated vertically positioned cylinder having a closed lower end, the upper end thereof being in communication with the atmosphere, a piston reciprocably mounted in the cylinder and adapted to be connected at its lower end to a pump rod extending through the lower end of the cylinder for operating the same, a closed hydraulic circuit for operating the piston including a centrifugal pump having its discharge connected to the lower end of the cylinder beneath the piston and its intake connected with an air balance tank, a prime mover connected to the pump for driving the same, said prime mover having an accelerated speed position sufficient to operate the pump at a rate producing an output sufficient to elevate the piston and its connected load through its upstroke and having a decelerated speed position so decreasing the output of the pump that the load on the piston will cause the same to descend through its down stroke and reverse the fluid flow through the pump, and a prime mover control means associated with the prime mover and responsive to changes in pressure in the cylinder at the ends of the piston stroke to effect a change of the prime mover operation from accelerated position at the upper end of the piston stroke to decelerated position and from decelerated posi-

tion at the lower end of the piston stroke to accelerated position.

4. A pumping jack including an elongated vertically positioned cylinder, a piston reciprocably mounted therein and adapted to be connected at its lower end to a pump rod for operating the same, the lower end of the cylinder being closed but through which the pump rod extends, the upper end of the cylinder being in communication with the atmosphere, a closed hydraulic circuit for operating the piston including a centrifugal pump having its discharge connected to the lower end of the cylinder beneath the piston and the intake connected with an air balance tank, said cylinder having a control port adjacent its upper end at a point below the piston when the piston is adjacent the end of its upper stroke, said cylinder having a lower control port adjacent its lower end at a point above the piston when the latter is adjacent the end of its down stroke, a prime mover for driving said pump, said prime mover having an accelerated speed position to drive the pump at an output capable of elevating the piston and its associated load through its upstroke and having a decelerated speed position reducing the output of the pump to a point where the load on the piston causes the same to lower through its down stroke, prime mover control means associated with the upper and lower control ports and responsive to pressure changes therat to effect a change of the prime mover operation from accelerated position to decelerated position when the piston moves to place the upper port in communication with the cylinder below the piston and from decelerated position to accelerated position when the piston moves to place the lower port in communication with the cylinder at a point above the piston.

5. A pumping jack including an elongated vertically positioned cylinder, a piston reciprocably mounted therein and adapted to be connected at its lower end to a pump rod for operating the same, the lower end of the cylinder being fluid tight, a closed hydraulic circuit for operating the piston, said circuit including a centrifugal pump having its discharge connected to the cylinder at a point below the piston and having its intake connected with an accumulator, means for operating the pump at a speed to produce an output sufficient to elevate the piston and its load through its upstroke, means for operating the pump at a decelerated speed after the piston reaches the top of the upstroke whereby the load on the piston will cause the piston to lower and reverse the direction of flow of fluid through the pump whereby the pump will act to restrict said fluid flow and aid in counterbalancing said piston load.

6. A pumping jack including an elongated vertically positioned cylinder, a piston reciprocably mounted therein and adapted to be connected at its lower end to a pump rod for operating the same, the lower end of the cylinder being fluid tight, a closed hydraulic circuit for operating the piston, said circuit including a centrifugal pump having its discharge connected to the cylinder at a point below the piston and having its intake connected with an accumulator, means for operating the pump at a speed to produce an output sufficient to elevate the piston and its load through its upstroke, means for operating the pump at a decelerated speed after the piston reaches the top of the upstroke whereby the load on the piston will cause the piston to lower and reverse the direction of flow of fluid through the

pump whereby the pump will act to restrict said fluid flow and aid in counterbalancing said piston load, and means for automatically effecting said speed change of the pump at the upper and lower ends of the piston stroke.

5 7. A pumping jack including a stationary elongated vertically positioned cylinder having a closed lower end, the upper end of the cylinder being in communication with the atmosphere, a piston reciprocably mounted in the cylinder and connected at its lower end to a pump rod extending through the lower end of the cylinder, a hydraulic circuit for operating the piston including a centrifugal pump having its discharge connected to the lower end of the cylinder beneath the piston and its intake connected with an air balance tank, pressure responsive pump control means for automatically causing increase of the pump output sufficiently to elevate the piston at the end of the downstroke thereof and to automatically decrease the pump output at the end of the upstroke thereof to enable the piston to lower under the influence of the load thereon at the end of the upstroke, and means for returning excess fluid along the upper end of the piston back into the hydraulic circuit.

8. A pumping jack including an elongated vertically positioned cylinder having a closed lower end, the upper end thereof being in communication with the atmosphere, a piston reciprocably mounted in the cylinder and adapted to be connected at its lower end to a pump rod extending through the lower end of the cylinder for operating the same, a hydraulic circuit for operating the piston including a centrifugal pump having its discharge connected to the lower end of the cylinder beneath the piston and its intake connected with a source of fluid, an internal combustion engine directly connected to the pump for driving the same, said engine having an accelerated throttle position for operating the pump at a speed producing an output sufficient to elevate the piston and its connected load through its upstroke and having a decelerated throttle position driving the pump at a speed that the load on the piston will be sufficient to cause the same to descend through its down stroke and reverse the fluid flow through the pump, and a pressure responsive control means associated with the engine and responsive to changes in pressure at the ends of the piston stroke to effect a change of the engine operation from accelerated throttle position at the upper end of the piston stroke to decelerated throttle position and from decelerated throttle position at the lower end of the piston stroke to accelerated throttle position.

9. A pumping jack including an elongated vertically positioned cylinder, a piston reciprocably mounted therein and adapted to be connected at its lower end to a pump rod for operating the same, the lower end of the cylinder being closed but through which the pump rod extends, the upper end of the cylinder being in communication with the atmosphere, a closed hydraulic circuit for operating the piston including a centrifugal pump having its discharge connected to the lower end of the cylinder beneath the piston and the intake connected with an accumulator tank, said cylinder having a series of vertically spaced control ports capable of being selectively made effective, said ports being disposed in the upper portion of the cylinder, said cylinder having a series of vertically spaced lower control ports in its lower portion and capable of being selectively made effective, a prime mover for driv-

ing said pump, said prime mover having an accelerated speed position to drive the pump at an output capable of elevating the piston and its associated load through its upstroke and having a decelerated speed position reducing the output of the pump to a point where the load on the piston would cause the same to lower through the down stroke of the piston, prime mover control means associated with the selected effective upper and lower control ports, and responsive to pressure changes thereat to effect a change of the prime mover operation from accelerated position to decelerated position when the piston moves to place the selected upper port in communication with the cylinder below the piston and from decelerated position to accelerated position when the piston moves to place the selected lower port in communication with the cylinder at a point above the piston.

10. A pumping jack including an elongated vertically positioned cylinder, a piston reciprocably mounted therein and adapted to be connected at its lower end to a pump rod for operating the same, the lower end of the cylinder being fluid tight, a closed hydraulic circuit for operating the piston, said circuit including a centrifugal pump having its discharge connected to the cylinder at a point below the piston and having its intake connected with a closed air balance tank, means for driving the pump at an output sufficient to elevate the piston and its associated load through the upstroke of the piston and for driving the pump at a decelerated speed after the piston reaches the top of the upstroke whereby the load on the piston will cause the piston to lower, reversing the direction of flow of fluid through the pump, whereby the pump will act to restrict said fluid flow and aid in counterbalancing said piston load.

11. A device of the character described comprising a variable speed motor having a speed control lever movable to high and low speed positions, a pressure responsive mechanism connected to said speed control lever whereby changes in pressure will cause said lever to move to a high or low speed position, whereby said motor will operate in a high or low speed, a centrifugal pump connected to and driven by said motor, said centrifugal pump having a fluid intake port and outlet port and being connected to a source of fluid at the intake port, a vertical cylinder being connected at its base to the outlet port of the centrifugal pump and open to atmospheric pressure at its upper end, a piston slidably mounted in said cylinder and adapted to be constantly urged toward the base of said cylinder and to be moved upwardly as fluid is pumped into the base of said cylinder, means secured to the lower portion of said cylinder to transmit atmospheric pressure to the pressure responsive mechanism whereby said speed control lever is moved to the high speed position when the piston is below said means secured to the lower portion of said cylinder thereby causing the output of the centrifugal pump to increase so as to force said piston upwardly in said cylinder, and means se-

cured to the upper portion of said cylinder to transmit the internal pressure of said cylinder to the pressure responsive mechanism thereby moving said speed control lever to the low speed position when the piston is above said means secured to the upper portion of the cylinder, thereby allowing the downward force of said piston to slowly force the fluid back through the centrifugal pump until the piston is once more below the means secured to the lower portion of said cylinder at which time the output of the centrifugal pump is again increased.

12. A device of the character described comprising a variable speed motor having a speed control lever movable to high and low speed positions, a pressure responsive mechanism connected to said speed control lever whereby changes in pressure will cause said lever to move to a high or low speed position, whereby said motor will operate in a high or low speed, a centrifugal pump connected to and driven by said motor, said centrifugal pump having a fluid intake port and outlet port and being connected to a source of fluid at the intake port, a vertical cylinder being connected at its base to the outlet port of the centrifugal pump and open to atmospheric pressure at its upper end, a piston slidably mounted in said cylinder and adapted to be constantly urged toward the base of said cylinder and to be moved upwardly as fluid is pumped into the base of said cylinder, said pressure responsive means comprising means secured to the lower portion of said cylinder responsive to high pressure in said cylinder to move from a first position to a second position and upon the release of pressure to move from said second position to said first position and being operable during the latter movement to move said speed control lever from a low speed position to a high speed position, said pressure being released when said piston moves to a position below the point of securement of the last named means to the cylinder, and means secured to the upper portion of said cylinder responsive to high pressure in said cylinder to move from a first position to a second position and operable during said movement to move said speed control lever from a high speed position to a low speed position, the last named means being subjected to high pressure when said piston moves to a position above the point of securement of the last named means to the cylinder.

JOHN CONLEY MASON.
